PARACHUTE

Peter J. Swofford, Fort Worth, Tex., assignor of
one-sixteenth to Tina Brooker Fife and one-
sixteenth to J. B. Hopson, both of Fort Worth,
Tex.

Application January 12, 1942, Serial No. 426,531

2 Claims. (Cl. 244—142)

This invention relates to parachutes, and has for one of its objects the production of a simple and efficient parachute which is provided with vertically extending cross fins for facilitating maneuverability and preventing the parachute from oscillating.

A further object of this invention is the production of a simple and efficient parachute which is so constructed as to prevent the entanglement of the shroud cords.

Other objects and advantages of the present invention will appear throughout the following specification and claims.

In the drawing:

Figure 1 is a side elevational view of the parachute;

Figure 2 is a transverse sectional view through the cross fins, taken on line 2—2 of Figure 1;

Figure 3 is a sectional perspective view of the cross fins.

By referring to the drawing, it will be seen that 10 designates the skirt portion of the chute canopy 9 which is formed of the conventional fabric used in constructing parachutes. The skirt portion 10 depends from the outer edge of the flat top portion 11, which flat top portion 11 is provided with a small central vent opening 12. As shown in Figure 2, the canopy 9 is preferably circular.

Elongated vertically extending fins 13 are arranged in crossed relation and depend from the flat top portion 11. These fins 13 taper toward their lower ends and are provided with cut-out portions 14 directly under the central vent opening 12 and under the center of the flat top portion 11 near their inner edges. These cut-out portions 14 provide an opening at the center of the canopy to permit air to equalize under the canopy of the chute. The fins 13 are formed of fabric and connect at their lower edge with cords 15.

The fins 13 are preferably about twelve feet long and extend below the bottom of the canopy 9, as shown in Figure 1. The fins 13 may be stitched or otherwise secured to the under face of the flat top portion 11. The cords 15 are secured at their lower ends to the harness 16. The flat top portion 11 will give the chute additional lifting power to off-set the weight of the additional material which is used in construction. Suitable rings 19 are carried by the harness 16 and the lower ends of the cords 15 and shroud cords 17 are connected to the conventional harness 16 and rings 19 as shown. The operator of the chute may easily reach up and grip the cords

15 to facilitate steering and to control his landing to a great degree. Due to the fact that the fins 13 are arranged in crossed relation, the chute will not drift or oscillate but will drop in an approximately vertical line.

By providing the fins which are arranged in crossed relation, I eliminate the possibility of entanglement of the cords. By providing four fins extending in crossed relation this structure 10 will eliminate oscillation of the chute and render the chute very maneuverable and act as a baffle. Furthermore, the chute when opened will descend downwardly in a substantially straight direction. The flat top which is provided will add greatly

15 to the lifting power of the chute and will add more power than would be provided otherwise, and will compensate for the extra amount of material as stated above which may be required to produce the chute. Furthermore, the arrangement of the fins will prevent the chute from turning over or spilling air. It should be noted that the fins are connected under the center of the chute, or the center ring thereof, directly under the flat top and the skirt 10 of the chute

15 when the chute is opened will depend from the edge of the flat top, as shown. Because of the fact that the fins 13 are secured to the under face of the flat top portion 11, the flat top portion will be held in a flat position and the bulging thereof will be resisted, the weight of the

20 operator of the chute pulling in a downward direction upon the shroud cords, and the lower ends of the fins. 25

The chute may be folded by folding the fins 35 in the direction of the arrows shown in Figure 2, and the portions of the canopy may be folded between these fins or the upper ends of the fins. I preferably provide three reinforcing cords 15 for each fin. The flat top portion is preferably

40 approximately 15 feet in diameter, and the skirt 10 is preferably three and one-half or four feet wide, cut in the conventional manner to provide a proper tapering form for the canopy.

It should be understood that certain detail changes in the construction may be employed without departing from the spirit of the invention, so long as such changes fall within the scope of the appended claims.

Having described the invention, what is claimed as new is:

50 1. A parachute of the class described comprising a canopy having downwardly turned edges, said canopy having a centrally located vent opening, vertical fins depending from and secured to the canopy beyond the vent opening and arranged

in cross relation relative to the vent opening, said fins having cut-out portions directly below the vent opening to direct air from between the fins and out through the vent opening at a point close to the under face of the canopy, thereby providing an air equalizer under the center of the canopy, said fins being connected together directly below the cut-out portions in spaced relation to the vent opening, and harness-engaging means suspended from the canopy and fins.

2. A parachute of the class described comprising a canopy having downwardly turned edges, said canopy having a centrally located vent opening, vertical fins depending from and secured to

the canopy beyond the vent opening and arranged in cross relation relative to the vent opening, said fins having cut-out portions directly below the vent opening to direct air from between the fins and out through the vent opening at a point close to the under face of the canopy, thereby providing an air equalizer under the center of the canopy, said fins being connected together directly below the cut-out portions in spaced relation to the vent opening, harness-engaging means suspended from the canopy and fins, a harness engaging the harness-engaging means, and said fins terminating short of the harness.

PETER J. SWOFFORD.
